(57) **CLAIM**

The ornamental design for a mesh spacer for reinforced concrete, as shown and described.

DESCRIPTION

FIG. 1 is a front perspective view of a mesh spacer for reinforced concrete showing my new design.

FIG. 2 is a front elevational view thereof, with the rear elevational view being the same as FIG. 2.

FIG. 3 is a left side elevational view thereof, with the right side elevational view being the same as FIG. 3.

FIG. 4 is a bottom plan view thereof; and,

FIG. 5 is a top plan view thereof.
